VACUUM CLEANER NOZZLE

Gordon W. Florian, Bridgeport, Conn., assignor
to Air-Way Electric Appliance Corporation,
Toledo, Ohio, a corporation of Delaware

Application January 7, 1949, Serial No. 108

Term of patent 14 years

(Cl. D9—2)

To all whom it may concern:

Be it known that I, Gordon W. Florian, a citizen of the United States and a resident of Bridgeport, Connecticut, have invented a new, original, and ornamental Design for a Vacuum Cleaner Nozzle, of which the following is a specification, reference being had to the accompanying drawings, forming a part thereof.

In the drawing:

Figure 1 is a front perspective view of the vacuum cleaner nozzle, showing my new design;

Figure 2 is a top plan view of the vacuum cleaner nozzle;

Figure 3 is a side elevation of the vacuum cleaner nozzle; and

Figure 4 is a sectional view on the line 4—4 of Figure 3 of the vacuum cleaner nozzle.

The characteristic features of my design reside in the portions shown in full lines.

I claim:

The ornamental design for a vacuum cleaner nozzle, as shown and described.

GORDON W. FLORIAN.
